UNITED STATES PATENT OFFICE.

CHARLES J. McGEE, OF OSCEOLA, ARKANSAS.

CLOTH-CUTTING MACHINE.

Application filed June 2, 1921. Serial No. 474,342.

To all whom it may concern:

Be it known that I, CHARLES J. McGEE, a citizen of the United States of America, and resident of Osceola, in the county of 5 Mississippi and State of Arkansas, have invented certain new and useful Improvements in Cloth-Cutting Machines, of which the following is a specification.

This invention relates to means for cutting 10 textile fabric and is intended for use more particularly in connection with the cutting of bagging or jute into appropriate lengths when they are arranged in superimposed layers.

15 An object of this invention is to provide novel means for permitting the movement of the webs of jute or fabric in order that they may be drawn over a table, means being also provided for clamping or holding the fabric 20 while the cutting operation is being performed.

A still further object of this invention is to provide a cutter and cutter operating mechanism adapted to be moved transversely 25 of the fabric support while the said material is being clamped to prevent the material from being disarranged while the cutting operation is being carried on.

It is furthermore an object of this invention 30 to produce a power machine designed to be operated by the drive shaft of any power plant, as an independent unit.

With the foregoing and other objects in view, the invention consists in the details of 35 construction, and in the arrangement and combination of parts to be hereinafter more fully set forth and claimed.

In describing the invention in detail, reference will be had to the accompanying 40 drawings forming part of this application wherein like characters denote corresponding parts in the several views, and in which—

Figure 1 illustrates a view in elevation of one end of the machine showing the manner 45 of operating the cutter;

Figure 2 illustrates a side elevation of the device with the cutter operating mechanism omitted;

Figure 3 illustrates a plan view of the 50 cutter;

Figure 4 illustrates an enlarged detail view of a tensioning device;

Figure 5 illustrates a plan view of the outer end of the clamp.

55 The application discloses a construction

embracing one embodiment of the invention, and the mechanism includes an elongated table 10 having transversely arranged guides 11 and 12 under the top thereof which form a track for the cutting frame 13 which cutting frame has an operating handle 14 by which it may be pulled to carry the knife 15 transversely of the table. As shown, the knife 15 is mounted on a shaft 16 having a pulley 17 engaged by a belt 18 and the said belt travels with the carriage from one side of the table to the other. Any suitable means may be provided for driving the belt by power applied to the shaft 19. A shaft 20 carries a pulley 21 and a pulley 22 is 60 mounted on the shaft 19. The shaft 20 is applied to an arm 23 hingedly mounted as at 24 to a post 25 so that the said arm may rise and fall, as shown in the full line and dotted line positions. It is intended that the weight 65 of the pulley 21 and parts associated with it, shall be sufficient to cause movement of the carriage to return it from the dotted line position shown in Fig. 1 to the full line position shown in Fig. 1, it being understood 70 that after the carriage receives momentum, it will travel to the said full line position.

The jute, bagging or fabric to be cut may be stored on rolls 26 and 27 rotatably mounted on a post 28, and of course, a 75 greater number of rolls may be mounted so that the webs or material therefrom may be drawn into interposed positions on the table, in order that a greater number of layers of material may be cut at one operation, but the 80 foregoing illustration will, it is thought, suffice as an understanding to those skilled in the art. As a means for preventing the displacement of the layers of fabric while the cutting operation is being carried on, a 85 clamp is mounted in operative relation to the table, and in the present embodiment of the clamp, a post 29 is supported in vertical position from the table at one side, the said post having a bracket 30 with an idler or 90 sheave pulley 31 thereon. A flexible member 32 operates over the idler and connects to the outer end of the clamp, as shown at 33. The 95 said clamp in the present embodiment includes two clamping elements 34 and 35 held in spaced relation to each other by the combined yoke and handle 36 at the outer end, the inner ends of the said members 34 and 35 being oscillatable on a shaft 37 with 100 heads such as 38 pressed down by springs 105 110

such as 39 or rods 40 applied to a supplemental frame 41. The flexible member 32 has a weight 42 which approximately counter-balances the weight of the clamp, and it 5 is effective to hold the clamp in the elevated position shown in Fig. 1. The clamping members are provided with a latch 43 which engages the lug 44 for holding the clamp in operative relation to the top of the table 10 while the cutting operation is carried on, and the said clamping members are returned to their elevated position by the weight 42. The springs 39 are effective and are of such strength as to press the pivoted end of 15 the clamp firmly against the cloth while the cutting operation is being carried on, and thus the clamp can be readily manipulated for holding or releasing the cloth, and the cutting operation can be performed by man- 20 ual pull on the handle of the cutter carriage,

the said carriage, as stated, being returned automatically to normal position by the weight of the elements associated with the oscillatable arm 23.

I claim:

In a cutter for cloth in superimposed layers, a table, guides transversely arranged in spaced relation to each other under the table, a carriage mounted for movement on the guides, a shaft rotatably mounted in the carriage, a cutter on the said shaft, a belt 30 operating over the shaft for driving the same, pulleys over which the said belt is operative, a hingedly mounted pulley engaging the said belt, means for moving the carriage in one direction and elevating the hingedly mounted pulley, the said pulley being operative to return the carriage to its 35 normal position.

CHARLES J. McGEE.
